Attorney.

UNITED STATES PATENT OFFICE.

CARL C. SPANGENBERGER, OF VENICE, CALIFORNIA.

ALIGNER FOR ENGINE PISTONS.

Application filed May 24, 1921. Serial No. 472,032.

To all whom it may concern:

Be it known that I, CARL C. SPANGENBERGER, a citizen of the United States, residing at Venice, in the county of Los Angeles and 5 State of California, have invented a new and useful Aligner for Engine Pistons, of which the following is a specification.

This invention relates to means for alining aviation, automobile, and other engine pistons perpendicular to the crank shaft, and 10 for finding twists in the connecting rods, and the main object of the invention is to provide convenient and effective means for this purpose which will ensure correct alinement with reference to the axis of the shaft.

The accompanying drawings illustrate the invention; and referring thereto:

Fig. 1 is a side elevation of the aligner in position for use, the engine shaft and 20 piston being indicated in dotted lines;

Fig. 2 is an elevation at right angles to Fig. 1.

The form of the invention shown in the drawings comprises a face plate 1 having a 25 finished or surfaced face 2 formed as a plane surface, said plate being mounted eccentrically on a stem or supporting rod 3 extending through a split clamping sleeve 4 on a supporting arm 5, said clamping sleeve being provided with a bolt or screw 6 for 30 tightening the same on the stem 3 whereby the face plate may be adjusted relatively to the supporting arm 5. On account of the eccentric mounting of the face plate 1 on the rod 3, said face plate extends farther 35 in one direction (the upward direction in position shown in Fig. 1) from its center of rotation than in the opposite direction, enabling it to be placed alongside the piston 40 in either up or down position of same, and to avoid interference with the crank pin in the upward throw thereof, the face plate being then placed in position shown in Fig. 1. The supporting arm 5 is provided with 45 a yoke member 7 on which is pivotally mounted at 8 a movable yoke member 9 adapted to be releasably held in position by means of snap catch or latch 10 pivotally mounted at 11 on the member 7 and adapted 50 to engage under a lug 12 on the movable yoke member 9, said lug being undercut to retain the parts in position. A bearing plate 13 is carried by a manually operated screw 14 and is adapted to engage the

crank pin of the engine shaft indicated at 55 15 to hold the same against a V-block 16 seated in the upper yoke 6. A number of interchangeable V-blocks 16 may be provided of different size to accommodate the device to shafts of different diameter. By 60 the bearing means consisting of the plate 13 and V-block 16 the device is rotatably mounted on the crank pin so as to provide for alinement of the piston in different positions. The aligner plate 2 is also rotatable in the supporting means 3 by loosening clamp 4 and turning rod 3 in said clamp, so that the said plate may be swung to position shown in Fig. 1, to aline the piston 70 when it is up, or to reverse position to aline the piston when it is down (the shaft being turned 180 degrees from the position shown in Fig. 1). By this means the piston may be alined throughout its stroke.

The device is used as follows: 75

The yoke member 9 is released from the yoke member 7 and said yoke members are placed around a throw or crank pin portion of a shaft, as indicated, a suitable V-block having been inserted to adapt the device 80 to the particular shaft for which alinement is to be made, the yoke member 9 being held in closed position by catch 10 and the screw 14 being operated to cause bearing plate 13 to press the shaft against the V-block, the 85 parts 16 and 14 then embracing and fitting on the shaft. The face plate 1 is adjusted by the clamping means 6 and 4 so as to bring it to proper position for engaging the cylindrical surface of the piston 17 corresponding to the next or adjacent throw or crank pin of the shaft and the piston is then alined so as to cause it to stand snug 90 and parallel to the finished surface of the plate. 95

To locate the twist in a rod it is only necessary to swing the face plate to one side and then bring the piston over to it again. If the piston does not stand snug and parallel to the plate it should be made to do so. 100 This operation is then reversed to the other side and finally to the center again to check up on it. The surface of the face plate being formed as a plane surface perpendicular to the axis of the crank pin and to the axis 105 of the engine shaft, the device may be used for detecting angular displacement of the piston pin, by swinging the piston on its

pin and noting whether it rides flat on the gauge plate surface as it should do if the piston pin is properly positioned.

What I claim is:

- 5 1. An aligner for engine pistons comprising supporting means adapted to embrace and rotatably fit on a crank pin portion of the engine shaft, and a face plate rotatably mounted on the aforesaid supporting means
- 10 to turn on an axis parallel to the axis of said shaft, said plate having an aligning face formed as a plane extending perpendicular to the axis of the shaft and adapted to engage the face of the piston connected to said shaft, said face plate being eccentrically mounted on its said support, so as to have a greater extension in one direction from its center of rotation than in the opposite direction.
- 15 2. An aligner for engine pistons comprising a face plate adapted to engage laterally

with the piston, a rod secured to said face plate, an arm having clamping means adjustably engaging said rod, a yoke member on said arm, a movable yoke member pivotally connected to aforesaid yoke member and a catch for holding said yoke members in closed position, said yoke members being provided with means for engaging a shaft and for holding the said face plate in a 30 plane perpendicular to the axis of the shaft.

3. An aligner, as set forth in claim 2, wherein said shaft engaging means comprise a V-block carried by one of said yoke members and means adjustably mounted in the 35 other of said yoke members for engaging the shaft to hold it in engagement with the said V-block.

In testimony whereof I have hereunto subscribed my name this 29th day of April, 40

CARL C. SPANGENBERGER,
